United States Patent Office

Des. 183,322

Patented Aug. 5, 1958

183,322

EMBROIDERED TEXTILE FABRIC OR SIMILAR ARTICLE

Morris Moskowitz, New York, N. Y.

Application September 11, 1957, Serial No. 47,704

Term of patent 3½ years

(Cl. D92—1)

The figure on the drawing is a plan view of a design for an embroidered textile fabric or similar article showing my new design.

The full width of the fabric is disclosed vertically and the design is repeated horizontally.

I claim:

The ornamental design for an embroidered textile fabric or similar article, substantially as shown and described.
